UNITED STATES PATENT OFFICE.

GUSTAF DE LAVAL, OF STOCKHOLM, SWEDEN.

CENTRIFUGAL LIQUID-SEPARATOR.

SPECIFICATION forming part of Letters Patent No. 372,783, dated November 8, 1887.

Application filed April 19, 1886. Serial No. 199,313. (No model.) Patented in Sweden January 29, 1886, No. 683; in France February 12, 1886, No. 174,126; in England February 12, 1886, No. 2,094; in Germany February 13, 1886, No. 38,315; in Austria-Hungary June 12, 1886, No. 6,796; in Norway August 30, 1886, No. 200; in Belgium October 21, 1886, No. 74,916; in Italy December 31, 1886, No. 75; in Victoria January 4, 1887, No. 4,870; in Tasmania January 8, 1887, No. 442, and in New South Wales March 2, 1887, No. 2,025.

To all whom it may concern:

Be it known that I, GUSTAF DE LAVAL, a subject of the King of Sweden and Norway, and a resident of Stockholm, Sweden, have 5 invented certain Improvements in Centrifugal Liquid-Separators, of which the following is a specification.

This invention has been patented in the following countries: Sweden, dated January 29, 10 1886, No. 683; France, dated February 12, 1886, No. 174,126; Great Britain, dated February 12, 1886, No. 2,094; Germany, dated February 13, 1886, No. 38,315; Austria-Hungary, dated June 12, 1886, No. 6,796; Norway, dated August 30, 1886, No. 200; Belgium, dated October 21, 1886, No. 74,916; Italy, dated December 31, 1886, No. 75; Victoria, dated January 4, 1887, No. 4,870; Tasmania, dated January 8, 1887, No. 442; New South Wales, dated 20 March 2, 1887, No. 2,025.

The invention relates to the construction of centrifugal apparatus that can be worked by hand-power for separating substances of different gravities, such as milk and cream.

25 A long separating-vessel is mounted upon a horizontal shaft, and is fitted thereto in two places and secured in such a manner that the separating-vessel, with openings at its respective ends, may be easily taken off the shaft, 30 which is provided with one or two friction-wheels resting upon one or two greater friction-wheels, secured on another shaft driven through wheels and a cord or gearing from a third shaft. The shaft carrying the separating-vessel is retained in place by pivoted arms so 35 formed as to embrace the bearings of the shaft, these arms being kept in place by springs that press against them.

40 This apparatus is represented in the accompanying drawings, in which Figure 1 is a longitudinal section in the line 1 1 of Fig. 2. Fig. 2 is a transverse section in the line 2 2, Fig. 1. Figs. 3 and 4 are respectively a transverse section and a plan or top view of a portion of 45 the apparatus. Figs. 5 to 12 are detached detail views of the apparatus hereinafter more particularly referred to, and Fig. 13 is a vertical section showing a modification of the driving-wheels.

50 *a* is the separating-vessel, arranged at or near its respective ends to fit enlargements or collars *c d*, of conical or other shape, on the horizontal shaft *b*, there being an inlet for milk in one end of the separating-vessel and outlets for the separated products at the other. 55 A spring hook or catch, *e*, in a recess in the enlargement or collar *d*, secures the vessel in place, or it may be otherwise fixed. The shaft *b* carries two small friction-wheels, *f f*, that rest upon two greater friction-wheels, *g g*. 60

The axes of the small friction-wheels *f f* may be in the same vertical plane with the axes of the driving-wheels *g g*; but it is preferred to arrange the axes of the small friction-wheels at one side of a vertical plane drawn through the axes of the driving-wheels *g g*, so that they shall not rest upon the highest parts of the greater friction-wheels *g g*. In this position the smaller friction-wheels *f f* and the shaft on which they are mounted are retained 70 by arms *k k*, pivoted at *i i*, (see Fig. 3,) and formed with recesses to embrace the bearings *h h* of the shaft, and pressed downward by springs at *l l*, carried by the lid or cover *m* of the apparatus. These bearings *h* are made as 75 two-part boxes recessed to receive collars upon the shaft and bolted together, so that said shaft is free to revolve in the bearings; but these bearings *h* remain upon the shaft when it is lifted out of the machine. 80

The shaft *n*, carrying the greater friction-wheels *g g*, is mounted in bearings supported by the end frames, *o o*, of the machine, which are connected by a bed-plate, *p*, and a top plate, *q*, thus forming a rigid and compact 85 stand. The shaft *n* receives rotary motion by means of a cord from a large wheel, *s*, (provided with a crank-handle, *r*,) which is mounted on a third shaft, the cord passing twice around a pulley, *t*, of conical shape, on the shaft *n*. 90 In lieu of this arrangement, spur-gear or friction-gear or other means may be employed to drive the shaft *n*.

Assuming that milk is to be treated to separate the cream from it, the milk is fed through 95 the pipe *u*, provided with a regulating-cock, to the separating-vessel *a*, through a regulating device comprising a vessel, *v*, Fig. 8, into

the upper part of which the pipe u projects, and which vessel is provided with a float, h' , (see Fig. 10,) whose upper end is of conical form, or is equivalently shaped to enter the lower end of the said pipe, so that according to the height of the float in its containing-vessel (depending upon the level of the milk therein) the inlet-orifice will be more or less obstructed, or it may be entirely closed. From the vessel v the milk is conducted through the small pipe w into the annular cavity x in the collar c , and thence during the rotary motion of the shaft the milk is thrown into the vessel a through the openings y (see Figs. 1, 11, and 12) in the said collar. At the other end of the separating-vessel a there is a pipe, z , with outlet z' for skimmed milk, and there is also an outlet, a' , for cream. These two outlets open, respectively, into two collecting-vessels, b' and c' , from which the separated products are discharged through suitable pipes, d' e' , respectively. The separating vessel a , the float-containing vessel v , and the collecting-vessels b' c' are inclosed in a casing, f' f'' , that serves to collect milk that may be spilled. This casing is provided with a discharge-cock, k' , and is made in two parts, of which the lower, f' , is secured to the stand and the upper, f'' , to the lid m .

In a modification represented in longitudinal section in Fig. 13 the apparatus is arranged to be worked by means of only one pair of friction-wheels. In this case the one bearing of the shaft b , carrying the separating-vessel a , can be supported in any suitable manner—such as by a bracket, m' , projecting from the stand—and the said shaft b has only one friction-wheel f , which rests on a greater friction-wheel g on the second shaft n . In this modification, instead of driving by cord and pulley, as in the arrangement hereinbefore described, the fly-wheel s is shown provided with teeth, which gear with a pinion on the shaft n .

To work the apparatus the fly-wheel s , which is provided with a crank-handle, r , is turned round by hand, and when the desired speed has been attained milk is introduced through the feed-pipe u , and the separated products run off through the discharge-pipes d' e' . (See Figs. 6 and 7.)

After each operation the apparatus should be carefully cleansed, and, as will be seen, its construction is particularly adapted to facilitate compliance with this important requirement.

For the purpose of cleaning, the milk-supply through the feed-pipe u having been shut off, that pipe is removed. Then the lid or cover m , with the attached upper part, f'' , of the casing, is raised and turned back on its hinges, as shown in Figs. 3 and 4. The arms k k , that secure the shaft-bearings h h in place, are also raised.

The vessel v has a stem at its lower end, and

rests upon the bearing v' upon the inside of 65 the case f' , into which the stem enters, and the pipe u discharges milk into the vessel v , and said vessel has a small curved pipe, w , which extends out horizontally near the bottom of the vessel v , and said vessel can be 70 turned sufficiently to cause the pipe w to enter or be withdrawn from the cavity x , (see Figs. 1, 4, 8, 9, and 11,) and after the lid m has been thrown back the vessel v and its float h' may be readily removed. The separating-vessel a 75 and the collecting-vessels b' c' are now free and loose, and can, together with the shaft b and its small friction-wheels f f (or wheel) and bearings h h , be removed from the stand. This being effected, the collecting-vessels b' c' 80 are removed, after which the shaft b , with the separating-vessel a upon it, is turned on end.

The catch e consists of a blade of sheet metal, one end of which is fastened upon the periphery of the collar d . The other end of the 85 catch has a head or knob, and when the vessel a is placed upon the shaft over the collars e d the head of the catch e enters a recess in the vessel and holds the same in place. To remove the vessel a from off the shaft b for 90 cleaning, it is only necessary to depress the exposed end of the catch e and strike the end of the shaft b (marked *) to loosen the collars e d from the vessel, so that the parts may be easily separated. Thus the parts to be 95 cleansed are separated from one another—namely, the inlet or regulating vessel v , Fig. 8, the regulating-float h' , Fig. 10, the discharge-vessels b' c' , Figs. 6 and 7, separating-vessel a , Fig. 5, and the shaft b , with its enlargements 100 or collars e d and bearings h h , Fig. 11. The inverse order is adopted in again putting the parts together.

I claim—

1. In a centrifugal separating apparatus, 105 the combination, with the vessel a , open at both ends, of the shaft b , the closed collar d , the spring-catch e upon said collar, and the circular ring-shaped and open collar c , substantially as specified.

2. In a centrifugal separating apparatus, 110 the combination, with the vessel a , shaft b , and mechanism, substantially as specified, for driving said shaft, of the bearings h h at the ends of the shaft, the retaining-arms k k , pivoted at i , and the springs l l , substantially as set forth.

3. In a centrifugal separating apparatus, 115 the combination, with the vessel a , having an open end, the casings f' f'' , and the bearing v' , 120 of the vessel v , supply-pipe u , float h' , and the curved pipe w , substantially as specified.

GUSTAF DE LAVAL.
